Inventor,
Ewald Hermsdorf,

by *J.W. Daher.*
Attorney.

UNITED STATES PATENT OFFICE.

EWALD HERMSDORF, OF BRUNSWICK, GERMANY.

APPARATUS FOR FEEDING POWDERED FUEL.

Application filed October 24, 1927, Serial No. 228,421, and in Germany November 5, 1928.

My invention relates to improvements in apparatus for feeding powdered fuel to a furnace, oven, or the like, and more particularly in apparatus of the type shown and described in the application for U. S. patent Ser. No. 743,125, filed October 11, 1924, (patented Sept 11, 1928, No. 1,684,320), in which the mixture of powdered fuel and air flows from a drum through a pipe disposed angularly of the said drum and into the combustion chamber. By thus deflecting the current of the mixture, the said current is obstructed within the laterally directed pipe, so that a reaction is exerted on the blower supplying the air to the mixing chamber.

The said reaction might be prevented by providing a fan at the joint of the drum and pipe. However, thereby the pressure of the blower would be increased, so that the advantage of the low pressure is lost. Therefore, for low pressure and large volumes of air the said fan can not be used.

The object of the improvements is to provide an apparatus in which the reaction of the air is prevented without materially increasing the pressure, and with this object in view my invention consists in providing a deflecting wheel at the delivery end of the drum, the diameter of the wheel being equal or substantially equal to the diameter of the mixing drum.

For the purpose of explaining the invention an example embodying the same has been shown in the accompanying drawing in which the same letters of reference have been used in all the views to indicate corresponding parts. In said drawing,

Fig. 1, is a sectional elevation of the apparatus, and

Fig. 2, is a section taken on the line 2—2 of Fig. 1.

In the example shown in the drawing the apparatus comprises a mixing drum *b* disposed with its axis horizontal, a receptacle *c* disposed above the said drum and containing powdered fuel, a blower *s* formed with helical blades or a similar air compressor

adapted to supply a large volume of air under low pressure, and a pipe *r* directed downwardly from the drum *b* and communicating therewith through an opening *a*, the said pipe being adapted to direct the mixture of air and powdered fuel to the combustion chamber. The powdered coal is supported within the receptacle *c* by means of a sieve *u* adapted to be acted upon by a hammer *v*, as has been described in the said prior application.

At the delivery end of the drum *b* a rotary deflecting wheel *l* is provided which is adapted to deflect the current of air and powdered fuel from the drum *b* into the pipe *r*. As shown the said deflecting wheel is mounted on the shaft *w* having the blower *s* mounted thereon, and it is provided with one or more blades *t*.

The mixture of powdered fuel and air is impelled by the blower *s* through the drum *b* and into the space occupied by the wheel *l*, and it is deflected by the blades of the said wheel downwardly and into the pipe *r*.

The cross-sectional area of the opening *a* corresponds to the volume of air and fuel to be delivered from the drum *b*.

I claim:

An apparatus for feeding powdered fuel to furnaces, ovens, or the like, comprising a mixing chamber, means for supplying powdered fuel to said mixing chamber, a delivery pipe disposed angularly of said mixing chamber, means for producing a current of air through said chamber towards said delivery pipe, and a rotating auxiliary propelling member at the delivery end of said mixing chamber for deflecting the current of air and fuel from the chamber to the delivery pipe, the said rotating member being adapted to direct the current of air and fuel into the pipe without materially increasing the pressure thereof.

In testimony whereof I have affixed my signature.

EWALD HERMSDORF.
